HEAT EXCHANGE DEVICE

Norris A. Scott, Jr., Mountain Lakes, N. J., assignee to Fester Wheeler Corporation, New York, N. Y., a corporation of New York

Application October 30, 1941, Serial No. 417,079

8 Claims. (Cl. 257—32)

This invention relates to heat exchange devices and more particularly pertains to heaters employed to preheat water or other fluid to be fed to a vapor generator by heat transferred from the steam or other condensable fluid introduced into the heater.

In heaters of this character, it is usual to provide a housing having therein a plurality of tubes through which fluid is passed to the vapor generator. Vapor from the generator is introduced into the housing and into contact with the tubes thereby heating the fluid passing therethrough. The condensate precipitated by contact of the vapor with the tubes together with any remaining uncondensed vapor is then withdrawn from the heater. Such heaters do not have a high degree of efficiency since the condensate withdrawn therefrom contains a high degree of heat.

The present invention provides an improved method of transferring heat and improved heat exchange apparatus in which fluid is heated by passing it in indirect heat exchange relationship with a condensable vapor and a maximum amount of heat is transferred from the vapor to the fluid.

The invention also provides an apparatus and method by means of which the fluid fed to a vapor generator is preheated by passing it in indirect heat exchange relationship with a condensable vapor and the condensate from the fluid heating section of the apparatus is passed through a separate condensate cooling zone in the apparatus.

The invention also provides an apparatus for heating fluid by heat transfer wherein the fluid carrying tubes may expand and contract without damage to the apparatus.

The features and advantages which characterize the invention will be apparent from the following description when considered in connection with the accompanying drawings forming a part thereof and in which:

Fig. 1 is a vertical sectional view of one form of apparatus embodying the invention;

Fig. 2 is a transverse sectional view taken on the line 2—2 of Fig. 1;

Fig. 3 is a view similar to Fig. 2 but taken on the line 3—3 of Fig. 1, and

Fig. 4 is a view similar to Figs. 2 and 3, but taken on the line 4—4 of Fig. 1.

Like characters of reference refer to the same parts throughout the several views.

Referring to the drawings, reference character 10 designates a substantially vertically extending cylindrical shell or housing forming a chamber 11 therein and flanged at the top to receive a

cover 12 which is held in a closed position by any desirable means and is tightly sealed by a gasket 12'. At the bottom thereof the shell 10 has a flange 13 with a circular projection 14 thereon adapted to be received in a circular recess 15 in a flange 16 on a cylindrical adapter piece 17. The flanges are held together by bolts or any other desirable means. A sealing gasket 18 is positioned between the flanges to form a seal therebetween. Extending transversely of the adapter piece 17 intermediate the opposite ends thereof is a partition 20 forming a chamber 21 in communication with the chamber 11 and a chamber 22 on the opposite side of the partition. The chamber 22 is closed by a bottom plate 23 held in position by a retaining ring 24 adapted to be received in a recess in the adapter piece. A watertight seal is provided between the chamber 22 and the bottom plate through a sealing diaphragm 25. A fluid inlet conduit 26, through which fluid to be heated enters the heater, is in communication with the inlet chamber 22, while an outlet conduit 27 is in communication with an outlet chamber 28 formed in the chamber 22 by partitions 29 separating the chambers 22 and 28 so that fluid cannot pass from one to the other.

Rolled into the partition 20 and extending upwardly therefrom is a plurality of tubes 30, some of which tubes designated 30' are in communication with the outlet chamber, while other tubes designated 30'' are in communication with the inlet chamber. Supported by the tubes at the top thereof is a floating head 31 into which the tubes are rolled. This head is recessed at 32 to receive a cover plate 33 held by a retaining ring 34 tightly against a shoulder 35 formed between the recess 32 and a smaller recess 36. A plate 37 resting on a shoulder in the recess 36 and spaced above the top of the tubes 30 forms a chamber 38 above the tubes. A sealing diaphragm 39 is positioned between the plate 37 and the cover plate 33 so as to seal the chamber 38 against leakage. The head 31 is of a slightly less diameter than the diameter of the chamber 11 and is positioned in spaced relationship to the cover 12 so that the head may have vertical movement in the shell 10 with the expansion and contraction of the tubes 30.

A group of tubes 30a nearest the cold water inlet 26 are enclosed in a shell 40 comprising a partition 40' between the tubes 30a and the tubes 30'' and a segmental partition 40'' spaced from the inner wall of the housing 10 and extending around the tubes 30a in spaced relationship

thereto, the opposite sides of the segmental partition being secured to the partition 40' in a fluid tight manner. The partition 40' is fastened in a fluid tight manner at the bottom to the partition 20 in the adapter piece and extends upwardly to a point short of the floating head. Another segmental partition 41, of a lesser radius than the segmental partition 40'', is fastened in a fluid tight manner at opposite sides to the partition 40' and encloses the tubes 30a from the partition 20 to which it is fastened in fluid tight relationship, upwardly to a point adjacent the flange 42. The partition 41 has a peripheral flange 42 which extends outwardly from the top of the partition 41 to the inner wall of the shell 10 against which it fits tightly. The segmental partition 40'', which has a greater radius than the partition 41, is secured in fluid tight relationship to the flange 42 and extends upwardly from the flange to a point short of the floating head 31. With this construction, a cooling chamber 49 is formed, around the tubes 30a which cooling chamber is of a greater radius above the flange 42 than below said flange. In decreasing the radius of the chamber 49 below the flange 42 by means of partition 41, a chamber 43 is formed between the outer periphery of the segmental partition 41 and the inner wall of the housing 10 which extends longitudinally of the housing between the partition 20 and the plate 42 and circumferentially of the partition 41 from the point of its connection at one side thereof to the partition 40' to the point of its connection at the opposite side to the partition 40'. The chamber 43 is in communication with the chambers 21 and 11 through a passage 44 formed between the partition 40' and a partition 45 which extends between the tubes 30'' and tubes 30' and from the partition 20 upwardly to a point a short distance therefrom. The partition 45 is connected to the partition 40' by a top piece 45'. The partition 45 has a passage 46 therein at one end thereof, while the partition 40' has a cut-out portion 47 therein adjacent the opposite end of the partition 45 and in communication with the chamber 43. The passage 46 is therefore in communication with the chamber 43 and chamber 21 respectively, through the cutout portions 47 and 46. Condensate flowing through the passage 46 will be precooled by contact with the tubes 30'' in this passage before entering the chamber 43 since cool fluid from the inlet 26 and chamber 22 flows through the tubes 30''.

The segmental partition 40'' together with the partition 40', is connected in sealed relationship to the floating head 31 by means of a cylindrical expansion connection 48. In this manner, a sealed cooling chamber 49 is formed around the tubes 30a between the segmental partition 40'' and the partition 40' which chamber is restricted to a slight degree below the flange 42 by the segmental section 41 so as to form the chamber 43. The expandable connection 48 permits movement of the floating channel 31 in relation to the partitions 40' and 40'' and at the same time prevents leakage between the chamber 11 and the chamber 49. The chamber 49 is vented at the top thereof by means of a vent pipe 51 which extends from the expandable connection 48 downwardly into the partition 20 and is vented to the atmosphere through a tube 51'.

The chamber 11 has a vent 63 in order that said chamber will not become air bound.

Through riser tubes 50 the chamber 43 is in communication with the chamber 49, the riser tubes extending upwardly from the flange 42 to a point short of the bottom of the floating head 31.

At the bottom, the chamber 49 is in communication with a condensate outlet conduit 52 which conduit extends through the housing 10 and chamber 43, the outlet conduit providing means by which condensate may be withdrawn from the chamber 49 without admixture with condensate in the chamber 43.

Preferably, a plurality of baffles 54 and 55 are used in chamber 49 for directing the flow of condensate therethrough and to support the tubes 30a. The baffles 54 project substantially horizontally at spaced points from the segmental partition 40' to a point short of the partition 40', while baffles 55 project from the partition 40' and are vertically so spaced as to be substantially intermediate the baffles 54.

A plurality of flow directing and tube supporting baffles also are preferably used in the chamber 11. The baffle 56, disposed substantially intermediate opposite ends of the shell 10, extends transversely of the chamber 11 horizontally between the partition 40' and a point short of the inner wall of the shell 10, the baffle being supported intermediate the partition and the wall by supports 57 disposed at opposite sides of the chamber 11. The chamber 11 has a vapor inlet conduit 58 in communication therewith adjacent the baffle 56, which has mounted thereon an impingement plate 59 adapted to deflect a stream of vapor from the vapor conduit 58 upwardly in the chamber 11 and also direct a stream of vapor downwardly in the chamber. Positioned on opposite sides of the baffle plate 56 and vertically spaced therefrom are baffle plates 60 which are fastened to vertically extending supports 57 and project therefrom horizontally toward the inner wall of the shell 10 substantially the same distance as the baffle 56.

Extending transversely of the chamber 11 from the supports 57 where they are connected by angles 56', to the partition 40' are vertically spaced baffles 61 which also bear a spaced relationship to baffles 60. Any desired number of these baffles may be used. Baffles 62, which are vertically spaced from each other, extend horizontally from the supports 57 to which they are attached at a point substantially intermediate the baffles 61 to the inner wall of the shell 10. The baffles 60, 61, 62, baffle 56 and impingement plate 59 cause the vapor entering the chamber 11 to pass upwardly and downwardly through the chamber in a tortuous path.

In operation, cool water, or other fluid to be heated, is passed into the chamber 22 through the inlet conduit 26 from which it is passed upwardly in the tubes 30a in the chamber 49, and the tubes 30' in the chamber 11. The chamber 49 is remote from the vapor inlet 58 and is sealed from the chamber 11. From the tubes 30a and 30', the fluid passes into the chamber 38 above the tubes and thence downwardly in the tubes 30' into the outlet chamber 28, whence it flows through the outlet conduit 27 to a point of use. In order that the fluid may be heated as it passes through the tubes 30, condensable vapor is passed into the chamber 11 through the vapor inlet conduit 58 where it impinges on deflector plate 59 which causes a stream of vapor to pass upwardly in the chamber 11 in a tortuous path around the baffles 60, 61 and 62. These baffles serve to sup-

port the tubes and to distribute the vapor so that it will flow over the tubes 30" and 30', the flow of vapor being countercurrent to the flow of fluid in the tubes 30' which are nearest the vapor inlet, and in the same direction as the flow of fluid in the tubes 30" which are remote from the vapor inlet. Condensate formed by contact of the vapor with the tubes flows downwardly over the baffles through the chamber 11 and into the chamber 21 to the bottom thereof. Any uncondensed vapor is directed downwardly over the tubes by contact with the bottom of the floating channel 31.

The impingement plate 59 also causes a stream of vapor to pass downwardly in the chamber 11, the vapor passing over the baffles 60, 61 and 62 in a tortuous path causing the vapor to be distributed over the tubes. The condensate formed by contact of the vapor with the tubes follows a like path over the baffles through the chamber 11 into the chamber 21 and to the bottom of said chamber. The level of the condensate is maintained above the top piece 45' as indicated by the water level line L in Fig. 1 of the drawings, so that steam will not pass from the chambers 11 and 21 into the chamber 43 and tubes 50, thereby preventing hammering in the cooling section. The condensate so formed is forced by the pressure in the chambers 11 and 21, caused by the pressure of the condensable vapor entering the chamber through the inlet 58, through the passage 46 into the passage 44 and thence into the chamber 43 through the cut-out portion 47 in the partition 40. As the condensate passes through the passage 44 it is precooled by contact with the tubes 31" in said passage and through which cool fluid from the chamber 22 passes. The precooled condensate rises from the chamber 43 through the riser tubes 50 and is discharged into the chamber 49 at the top thereof adjacent the floating head 31. While the condensate is rising in the tubes 50 it is cooled further since the tubes 30a passing through the chamber 49 are cooled by cold fluid flowing through them, the tubes cooling the chamber 49 which is sealed from the vapor entering the chamber 11 through the inlet 58. The condensate passing into the chamber 49 from the riser tubes 50 flows downwardly through the chamber over the baffles 54 and 55 countercurrent to the flow of fluid in the tubes 30a and is cooled by further contact with these tubes. The condensate passes to the bottom of the chamber 49 and thence outwardly through the outlet conduit 52.

Thus, it will be perceived that the invention provides a fluid heater and a heat transfer method in which the vapor used for heating the fluid is condensed and the condensate thoroughly cooled through the provision of a separate cooling section in the heater or in the heating zone. The construction and arrangement of parts provides maximum efficiency and will not be subject to lowering efficiency due to short circuiting or by-passing of steam or other vapor into the separate cooling section.

As used herein and in the claims, the term "vapor" includes "gas."

Although a preferred embodiment of the invention is disclosed herein, it is to be understood that changes may be made in the particular form and relative arrangement of the various parts of the apparatus described without departing from the principles of the invention. For example, the baffles may be arranged otherwise

than as disclosed, or the baffles may be omitted if desired. Accordingly, the invention is not to be limited excepting by the scope of the appended claims.

5. What is claimed is:

1. A heat exchanger comprising a shell, a first group of substantially vertically extending tubes in the shell, said tubes being fixedly mounted at one end thereof in the shell, a tube sheet to which the opposite end of the tubes are connected and movable longitudinally of the shell upon axial expansion and contraction of the tubes, an inlet in the shell through which condensable fluid is supplied under pressure, a second group of tubes, partition means in the shell forming a chamber around the second tube group and for separating the second tube group from the first tube group, said partition being fixedly mounted in fluid tight manner at one end thereof and extending to a point short of the movable tube sheet, an expandable member between the partition and the movable tube sheet, means for supplying a fluid to said second group of tubes for flow therethrough and then through the tubes of the first group, an outlet through which fluid passes after flowing through said first group of tubes, the condensate formed by passage of the condensable fluid in heat exchange relationship with the tubes of the first group collecting at the lower end of said first group of tubes an upwardly extending tubular member in said chamber adapted to discharge into said chamber adjacent the upper end thereof, enclosed passage means in communication with the condensate collected at the lower end of the first group of tubes and with the lower end of the upwardly extending tubular member through which tubular member condensate is forced upwardly by the pressure of the condensable fluid in the shell and is discharged thereinto to flow downwardly in heat exchange relationship with the tubes therein, and an outlet in the lower portion of the chamber through which condensate is withdrawn therefrom.

45. 2. A heat exchanger comprising a shell having separated inlet and outlet chambers at the bottom thereof, an inlet through which a cooling fluid is admitted to the inlet chamber, an outlet through which heated fluid passes from the shell, a tube sheet forming a top for said chambers, a first group of substantially vertically extending tubes in the shell connected to said tube sheet a plurality of which are in communication with the outlet chamber, an inlet in the shell through which condensable fluid under pressure is supplied, the condensate formed by passage of said fluid in heat exchange relationship with the tubes of the first tube group collecting at the lower end of said first group of tubes, a second group of substantially vertically extending tubes, said tubes being connected to the tube sheet and in communication with the inlet chamber and with the first tube group so that fluid flows from the second tube group into the first tube group, means in the shell for forming a condensate cooling chamber around said second group of tubes, an upwardly extending tubular member in the cooling chamber adjacent the tubes of said second group, partition means in the shell forming an enclosed passage in communication with the condensate collected at the lower end of said first group of tubes and through which condensate flows to the tubular member, the arrangement being such that the condensate is forced upwardly in the tubular member by pressure of the

condensable fluid in the shell through at least part of the cooling chamber and discharged thereinto to pass downwardly in heat exchange relationship with the tubes therein, and an outlet in the lower portion of said cooling chamber through which condensate is withdrawn from said chamber.

3. A heat exchanger comprising a shell having separated inlet and outlet chambers at the bottom thereof, an inlet through which a cooling fluid is admitted to the inlet chamber, an outlet in communication with the outlet chamber through which heated fluid passes from the shell, a first group of substantially vertically extending tubes in the shell a plurality of which are in communication with the outlet chamber, an inlet in the shell through which condensable fluid under pressure is supplied, a second group of substantially vertically extending tubes in communication at one end with the inlet chamber and with said plurality of tubes of the first tube group which are in communication with the outlet chamber, the condensate formed by passage of the condensable fluid in heat exchange relationship with the tubes of the first group collecting at the lower end of said first group of tubes, a condensate cooling chamber around the second group of tubes, upwardly extending tubular members in the cooling chamber, partition means above the inlet chamber forming a passage through which tubes conducting cooling fluid from the inlet chamber pass, said passage being in communication with the condensate collected at the end of said tubular first group of members, means for conducting the condensate from said passage above the inlet chamber to the inlet end of the upwardly extending tubular members, the outlet end of the tubular members discharging into the cooling chamber, the arrangement being such that the condensate is forced upwardly in the tubular members by pressure of the condensable fluid in the shell through at least part of the cooling chamber and discharged thereinto to pass downwardly in heat exchange relationship with the tubes therein, and an outlet in the lower portion of said cooling chamber through which condensate is withdrawn from said chamber.

4. A heat exchanger comprising a shell having separated inlet and outlet chambers at the bottom thereof, an inlet through which a cooling fluid is admitted to the inlet chamber, an outlet in communication with the outlet chamber through which heated fluid passes from the shell, a first group of substantially vertically extending tubes in the shell, some of said tubes being in communication with the inlet chamber and other of the tubes being in communication with the outlet chamber, an inlet in the shell through which condensable fluid under pressure is supplied, a second group of substantially vertically extending tubes in communication at one end with the inlet chamber and with said tubes of the first tube group which are in communication with the outlet chamber, the condensate formed by passage of the condensable fluid in heat exchange relationship with the tubes of the first group collecting at the lower end of said first group of tubes, a condensate cooling chamber around the second group of tubes, upwardly extending tubular members in the cooling chamber, partition means in said condensate collecting means forming a passage through which the tubes of the first tube group which are in communication with the inlet chamber pass, said passage

being in communication with the condensate collected at the end of said first group of tubular members, and means for conducting the condensate from said passage above the inlet chamber to the inlet end of the upwardly extending tubular member, the outlet end of the tubular members discharging into the cooling chamber, the arrangement being such that the condensate is forced upwardly in the tubular members by pressure of the condensable fluid in the shell through at least part of the cooling chamber and discharged thereinto to pass downwardly in heat exchange relationship with the tubes therein, and an outlet in the lower portion of said cooling chamber through which condensate is withdrawn from said chamber.

5. A heat exchanger comprising a shell, a bank of tubes in the shell, longitudinally extending partitioning means in the tube bank dividing it into completely separated first and second laterally disposed tube groups, means for supplying a fluid to the inlet ends of the tubes of the bank for flow therethrough and discharge at the outlet ends thereof, means for supplying a condensable fluid under pressure to the interior of the shell for contact with the tubes of the first tube group, the shell, tubes and associated parts being arranged and disposed so that condensate of the condensable fluid collects in a zone adjacent one end of

10 the tube bank and adjacent the tubes of the first tube group, separate tubular members disposed in the shell adjacent to and at the same side of the partitioning means as the tubes of the second tube group and substantially parallel thereto, 15 said separate tubular members extending to a point adjacent the opposite end of the tube bank of the second tube group, conduit means connecting the zone adjacent said one end of the first tube group with the corresponding ends of said

20 separate tubular members, the pressure of the condensable fluid causing the collected condensate to flow through said separate tubular members to said opposite end portion of the second tube group, and means providing an outlet for the condensate from the shell adjacent said one end of the tube bank and adjacent the tubes of the second tube group, whereby the condensate is caused to flow in contact with those portions of the tubes of the second tube group extending intermediate said opposite end and said one end of the tube bank.

6. A heat exchanger comprising a shell, a bank of substantially vertically extending tubes in the shell, longitudinally extending partitioning means in the tube bank dividing it into completely separated first and second laterally disposed tube groups, means for supplying a fluid to the inlet ends of the tubes of the bank for flow therethrough and discharge at the outlet ends thereof,

25 means for supplying a condensable fluid under pressure to the interior of the shell for contact with the tubes of the first tube group, the shell, tubes and associated parts being arranged and disposed so that condensate of the condensable fluid collects in a zone adjacent the lower end of the tube bank and adjacent the tubes of the first tube group, separate tubular members disposed in the shell adjacent to the tubes of the second tube group and at the same side of the partitioning means as the second tube group and substantially parallel thereto, said separate tubular members extending to a point adjacent the upper end of the tube bank of the second tube group, conduit means connecting the zone adjacent said

30 lower end of the first tube group with the corre-

sponding ends of said separate tubular members, the pressure of the condensable fluid causing the collected condensate to flow through said separate tubular members to said upper end portion of the second tube group, and means providing an outlet for the condensate from the shell adjacent the lower end of the tube bank and adjacent the tubes of the second tube group, whereby the condensate is caused to flow in contact with those portions of the tubes of the second tube group extending intermediate said upper end and the lower end of the tube bank.

7. A heat exchanger comprising a shell, a bank of tubes in the shell, longitudinally extending partitioning means in the tube bank dividing it into completely separated first and second laterally disposed tube groups, the tubes of the first and second tube groups being in communication, means for supplying a cooling fluid to the tubes of the second tube group for flow therethrough and then through the tubes of the first group, means for supplying a condensable fluid under pressure to the interior of the shell for contact with the tubes of the first tube group, the shell, tubes and associated parts being arranged and disposed so that condensate of the condensable fluid collects in a zone adjacent the lower end of the tube bank and adjacent the tubes of the first tube group, separate tubular members disposed in the shell adjacent to and at the same side of the partitioning means as the tubes of the second tube group and substantially parallel thereto, said separate tubular members extending to a point adjacent the opposite end of the tube bank of the second tube group, conduit means connecting the zone adjacent said one end of the first tube group with the corresponding ends of said separate tubular members, the pressure of the condensable fluid causing the collected condensate to flow through said separate tubular members to said opposite end portion of the second tube group, and means providing an outlet for the condensate from the shell adjacent said one end of the tube bank and adjacent the tubes of the second tube

group, whereby the condensate is caused to flow in contact with those portions of the tubes of the second tube group extending intermediate said opposite end and said one end of the tube bank.

8. A heat exchanger comprising a shell, a bank of substantially vertically extending tubes in the shell, longitudinally extending partitioning means in the tube bank dividing it into completely separated first and second laterally disposed tube groups, the tubes of the first and second tube groups being in communication, means for supplying a cooling fluid to the tubes of the second tube group for flow therethrough and then through the tubes of the first group, means for supplying a condensable fluid under pressure to the interior of the shell for contact with the tubes of the first tube group, the shell, tubes and associated parts being arranged and disposed so that condensate of the condensable fluid collects in a zone adjacent the lower end of the tube bank and adjacent the tubes of the first tube group, separate tubular members disposed in the shell adjacent to the tubes of the second tube group and at the same side of the partitioning means as the second tube group and substantially parallel thereto, said separate tubular members extending to a point adjacent the upper end of the tube bank of the second tube group, conduit means connecting the zone adjacent said lower end of the first tube group with the corresponding ends of said separate tubular members, the pressure of the condensable fluid causing the collected condensate to flow through said separate tubular members to said upper end portion of the second tube group, and means providing an outlet for the condensate from the shell adjacent the lower end of the tube bank and adjacent the tubes of the second tube group, whereby the condensate is caused to flow in contact with those portions of the tubes of the second tube group extending intermediate said upper end and the lower end of the tube bank.
